OPERATING MECHANISM FOR DOMESTIC IRONING MACHINES AND THE LIKE

James F. Young, Bridgeport, Conn., assignor to
General Electric Company, a corporation of
New York

Application December 22, 1949, Serial No. 134,473

5 Claims. (Cl. 38—25)

1

This invention relates to domestic ironing machines of the flatplate type, and in particular to an improved mechanism for operating the pressing elements thereof in timed relation.

Domestic flatplate ironing machines generally include a padded ironing table—known in the art as a “buck”—on which the articles to be ironed are laid by the operator; and a heated “shoe” which is carried on an arm structure pivoted relative to the buck to be brought into pressing position with relation thereto. By suitable mechanism the respective elements are then brought together to press the articles therebetween. A commercially popular ironing machine of this type is shown in the Wardwell, Jr. Patent No. 2,135,266 granted November 1, 1938 for “Ironing Machine.” In the machine disclosed therein the shoe is moved manually, and as it approaches the ironing position switch means are automatically closed to energize a hydraulic motor system which drives the buck upwardly against the shoe.

My invention has for its main objectives the provision of improved means for automatically bringing both the shoe and the buck into ironing position; the provision of simple mechanical means for controlling the acceleration of the co-operating press elements; the provision of means for reducing extraneous forces on the buck operator as the shoe comes into operating position so as to make full pressure available for the ironing operation; the provision of pressure operated valve means in the hydraulic motor system to govern the rate of rise and return of the pressing elements; and the provision of adjustable relief means to obtain substantially uniform operation of the hydraulic motor system despite, for example, variations of viscosity of the liquid content of the system and subnormal line voltage available for operation of the motor.

In a presently preferred embodiment of my invention I accomplish these and other objects and advantages by associating operatively the hydraulic motor unit and the shoe carriage through a linkage system including camming means arranged to produce variant rates of travel of the shoe carriage during its movement to operative position notwithstanding substantially uniform rate of operation of the motor unit. I have improved the fluid pressure generator element of the hydraulic motor unit by the provision of pressure operated valve members which establish one rate of pressure application against the piston of the motor as the shoe is rising, and relatively larger facilities and more rapid flow rate for the return flow of fluid so as to speed the return of

2

the motor piston—and correspondingly the return movement of the shoe and buck—after the ironing operation. Such return is nevertheless accomplished smoothly because of the dashpot action of the piston and cylinder. The shape of the shoe carriage cam relieves the load on the motor as the shoe comes into position, and the buck accelerates its upward movement at the completion of its stroke.

In the accompanying drawing Fig. 1 is a side elevation of an ironing machine showing in full line the shoe and buck in retracted or “home” position and in dotted line relative intermediate positions of these elements during their operation; Fig. 2 is a front elevation of the shoe drive linkage looking in the direction of the arrows 2—2 of Fig. 1; Figs. 3, 4, 5, and 6 are representative of the cam operation of the shoe linkage mechanism; Fig. 7 is a sectional side elevation of a hydraulic motor unit embodying the present invention, the section being taken on lines 7—7 of Fig. 8; and Fig. 8 is a top plan view of the piston head plate, showing the pump cavity and valved outlet passages.

Referring now to Fig. 1, a domestic ironing machine of the flatplate type includes a frame structure 1 which is arranged in the form of a table having a rigid top 2 on which is mounted a cylinder 3 within which operates the hydraulic motor unit. As later explained, said unit carries the buck 4 and is arranged to drive said buck upwardly to exert ironing pressure against a heated shoe 5 which had previously come into operating position. The shoe is carried by a rigid, substantially U-shaped, carriage 6 pivotally supported on hangers 7 extending from the cylinder 3. Desirably said hangers are integral with the cylinder. The cylinder is provided with a flange structure 8 disposed at an angle relative to the cylinder axis so as to support the cylinder in an angular relation with respect to the table top, as viewed in side elevation. The lower portion of the cylinder projects through an opening provided in the table top. Generally speaking, said structure is not essentially different from that shown in the aforementioned Wardwell Patent No. 2,135,266. The shoe carriage may be cushioned at the extremities of its travel toward or away from the buck by suitable means such as the pairs of springs 9, 10 carried on rods 11 pivotally affixed beneath the table top 2 at the sides of the cylinder 3. Suitable adjustment nuts 12, 14 are provided to regulate the tension of the springs, which respectively bear against a bracket 15 slidably mounted on the respective rods 11.

Each bracket is pivotally attached to an arm 16 affixed to the carriage 6. It will be apparent that as the shoe arm rotates clockwise of Fig. 1 the spring 9 is compressed and that said spring may assist the return of the carriage. The spring 10 cushions the carriage at the end of its return movement. It should be understood that the buck and the shoe are elongate and of substantial area, and that each is symmetrical with respect to the cylinder 3.

I mechanically drive both the buck and the shoe carriage from the hydraulic motor device 17 disposed within the cylinder 3. Broadly speaking, the motor unit comprises a combination piston and pressure generator which pumps fluid into a space between the cylinder head and the piston head to drive the piston within the cylinder. As shown in Fig. 7, the unit has a piston-like structure 18 having a compartment in which is mounted an electric motor 19, to the shaft of which is connected an impeller 20 operating within a pump chamber 20a of double involute form (see Fig. 8) provided by the respective wall members 21, 22, the latter being the actual piston head. The wall members 21, 22 may be bolted together, as shown, and accommodate a piston ring 23. Other wall members disposed intermediate the ends of the piston 18 similarly provide a seat for a piston ring 24. A cap 25 is affixed to the end of the piston, and fixedly carries a frame 26 having outwardly extending members 27 on which the buck 4 is suitably mounted.

The cylinder 3 normally contains a charge of fluid, usually a light mineral oil, which occupies the cylinder to a level immediately below the upper piston ring flanges. The oil is in communication with the impeller pump chamber through the apertures 28 and the pump chamber inlet 29. When the motor 19 is energized, as by closing an electric circuit including a foot pedal actuated switch 30, the impeller 20 generates hydraulic pressure which is discharged into a chamber 31 below the piston head, as presently explained. The hydraulic pressure reacts against the piston head to drive the structure 18 upwardly to propel the buck 4.

It is my belief that the operative connection between the piston means and the shoe carriage is best accomplished by a balanced linkage arranged for a centered, single point engagement with the carriage. Accordingly, in the illustrated presently preferred embodiment, I affix to the cap member 25 a strap 32 having diametrically opposed ends 33 extending through suitable slotted openings in the upper wall of the cylinder 3. To said ends 33 I pivotally affix the link members 34 which in turn are pivoted to an arcuate yoke structure 35, secured relative to the table top 2 by pivotal attachment 45 to brackets 36 thereon. Said yoke is, of course symmetrical with respect to the piston structure 18. A cross-bar 37 of the yoke extends beneath the shoe carriage 6 and carries a roller 38 supported by the mounting brackets 39. As best appears in Fig. 2, the lower wall 40 of the carriage 6 has an elongate opening at its extremity within which is centered a cam member 41 rigidly carried by the brackets 42 for engagement by roller 38. Advantageously, and as shown in Fig. 1, the end 43 of the cam may abut the top wall of the carriage 6 for securement thereto.

In the operation of an ironing machine, it is desirable that the shoe move rapidly during the first portion of its relatively long movement from the retracted to the operative position but that

until the shoe comes into position the buck have a relatively short, slow movement. Not only does such relationship afford the operator an opportunity to perform any last instant smoothing of the article on the buck, but there is assured an adequate clearance between buck and shoe when ironing heavy articles, such as blankets or trousers. The rate of movement of the shoe preferably lessens as the shoe approaches ironing position and the buck rate of rise desirably increases, with minimum of extraneous load on the buck so that the maximum of motor force is applicable for the actual pressing operation. Such pattern of movement may be accomplished with a simple, inexpensive cam construction by utilizing to advantage the changing force application relationships between the cam surfaces and the cam driving member as the shoe carriage moves from retracted to pressing position. In the somewhat schematic cam representations of Figs. 3 and 6 it should first be noted that the point 44 thereof corresponds to the pivot point of the carriage 6, and in Fig. 6, the point 45 represents the pivot 45 of yoke 35. The cam 41 has the mutually angularly associated surfaces 46, 47, 48 along which the roller 38 travels as the yoke 35 is rotated by the operation of the hydraulic motor unit 17. The motor piston moves relatively slowly within the cylinder, and correspondingly the buck rises slowly, but the angular relation of the cam surface 46 to the path of movement of the roller 38 is such as to translate the piston movement into an immediate relatively rapid rotation of the carriage 6, as is apparent by comparison of carriage positions III and IV of Fig. 1, which correspond to the cam representations of Figs. 3 and 4. The application of force of roller 38 during this phase is substantially normal to the cam surface 46, and in view of the short lever arm between pivot 44 and the point of engagement of roller 38 with the cam, the small rise of the roller effects the illustrated angular rotation of the carriage 6. At Fig. 5 the early relationship between the arc of movement of roller 38 and the cam surface 46 has changed, and the carriage movement becomes less rapid, as indicated by comparison of positions IV and V of Fig. 1. There is a further deceleration as the roller enters upon cam face 47. Then as the roller 38 transfers from surface 47 to surface 48 the shoe movement becomes relatively small, as indicated by the comparison of positions V and VI of Fig. 1. As a matter of fact, at Fig. 6 the roller 38 is doing very little work on the carriage 6 because it will be noted that the cam surface 48 makes a very small angle with the arcuate path of roller 38. Therefore, between the positions V and VI the shoe load has practically been eliminated from the hydraulic motor unit. The final movement of the shoe and its carriage is aided by the shifting center of gravity thereof; the motor unit is at this stage primarily concerned with compressing springs 9 so that the reaction thereof will hold the carriage securely against the roller 38 and will provide sufficient storage of forces to throw the shoe and carriage rearwardly to an overcenter position for the return to retracted position.

The movement of the motor unit 17 within cylinder 3 is controlled by valves 50 which slidably operate in channels 51 formed in plate 22 at the respective extremities of the involute pump chamber 20a. The plate 22 is provided with apertures of markedly different diameter, the larger apertures 52 being at the outermost ends of the grooves 51 so as to be actually externally

of the pump chamber and the smaller apertures 53 being substantially at the entrance end of said grooves. Apertures 52 provide direct communication between chamber 31 and the liquid reservoir. The valve members 50 may comprise plate-like elements in slidable engagement with the walls of the grooves and the bottom of plate 21 so as to have a substantially leak proof association with said walls. The spring members 54 bias the valves to occupy a normal position which exposes the openings 52 and covers openings 53. At the instant of operation of the impeller 20 therefore the hydraulic fluid has no escape from the impeller chamber and its first action is to drive the valve members 50 along channels 51 until the openings 53 are uncovered whereupon the hydraulic fluid enters the chamber 31. The hydraulic unit drives upwardly at the rate determined by the rate of flow of liquid through the discharge openings 53. The governing effect of the restrictions to impeller discharge provided by the openings 53 make the operation of the motor unit substantially uniform throughout a motor voltage range of from 90 to 130 volts. It should be understood that the openings 52 are closed by the valve members 50 when the latter have opened the ports 53 thus preventing any bypassing of hydraulic pressure through openings 52 to above the piston head. After the pressing operation has been completed the operator opens the switch 30 to de-energize motor 19 and the springs 54 drive the valve members 50 to expose the relatively large ports 52 and permit the weight of the buck to move the piston unit 17 downwardly, oil returning to the cylinder above the piston head through said passages 52. Springs 9 keep the shoe carriage in engagement with the cam roller 38 until the overcenter gravity position of the shoe and carriage is reached, following which such engagement is inherently maintained. The dashpot effect of the oil ports 52 is thus available to smooth the return movement of the shoe as well as the buck. The buck rises slowly during its initial movement, and accelerates during its upward travel as the load imposed on the motor unit by the shoe and carriage becomes less.

It will be observed that with the releasable cam and roller arrangement of my invention the shoe carriage may manually be brought forward—for example, to position the shoe carriage for the use of the usual cover or enclosure (not shown) with which ironers of this type are usually provided.

Speed control of the buck and other operating advantages may be accomplished also by the inclusion of a pressure relief circuit in cylinder 3, arranging said circuit so that its downstream end enters the cylinder at a point coinciding with the up position of the shoe so that further motion of the piston will apply equal pressure to both sides of a pressure relief valve element to take the same effectively out of service. At this point, therefore, maximum fluid pressure will be available for the actual ironing operation. A suitable relief valve organization is shown in Fig. 7. A valve body 55 shaped to the curvature of the cylinder may be welded or otherwise secured thereto in leak-proof relationship. The valve body is bored to provide a flow circuit comprising the interconnected upstream and downstream legs 56, 57 which communicate with the cylinder as shown. A sleeve 58 is fixed to the valve body in pressure tight relation therewith; said sleeve may be internally threaded

to receive the valve stem guide member 60 within which slidably operates a poppet type valve 61 biased by spring 62 into seated relation with respect to passage 56. By means of the suitably affixed adjustment knob 63 the member 60 may be rotated for movement axially within sleeve 58 so as to establish a desired spring bias against valve 61.

It will be noted from Fig. 7 that with the piston in home position the upstream passage 56 is taken out of service by the respective piston elements 21 and 22. Initially therefore the fluid pressure is available at maximum level to overcome starting inertia of the operating elements. It has been noted that the cam drive of the shoe carriage effects maximum rotation of the carriage toward operating position during the very early stages of piston lift. Therefore by the time the upstream passage 56 is sufficiently cleared by the piston head to become operatively effective, the shoe carriage will have completed the greater portion of its travel. Therefore, by suitable adjustment of the valve bias, the operator may control the rate of movement of the buck and of the shoe during the final drive to operating position. For example, by reducing the spring bias, a portion of the oil discharging through the ports 53 may be by-passed above the piston head thereby effectively slowing the piston drive. Conversely by increasing the spring bias one may appropriately reduce oil flow through the by-pass structure. In any event, it should be noted that if at any instant before the piston head assembly covers the downstream passage 57 abnormal restraint against the movement of the shoe carriage or buck develops—for example if the operator in an emergency sought to hold back the shoe while leaving switch 30 closed—the hydraulic pressure with the chamber 31 will be expanded in passage through the relief circuit and the ironer will not be exposed to damaging strains. After the piston has risen fully, at which time the shoe is in ironing position, the downstream port 57 is closed and the balance of pressure on each side of the valve 61 makes full pressure available against the piston head 22 for exertion of full ironing pressure.

While I have shown a particular embodiment of my invention, it will be understood, of course, that I do not wish to be limited thereto since many modifications may be made; and I therefore contemplate by the appended claims to cover any such modifications as fall within the true spirit and scope of my invention.

What I claim as new and desire to secure by Letters Patent of the United States is:

1. In an ironing machine having a frame structure, a buck, a shoe, and a shoe carriage pivotally supported relative to said buck for movement between a retracted position with the shoe remote from the buck and an operating position placing the shoe in register with the buck, the improvement in means for conjointly propelling said buck and said shoe carriage into operative relationship comprising a motor unit including a cylinder fixed relative to said frame and pivotally carrying said shoe carriage, piston means within the cylinder and means for propelling the piston therein, said buck being secured to said piston, a yoke pivoted relative to said frame and extending into operative relationship with the shoe carriage, said yoke having an element in engagement with said carriage at a point spaced from its axis of rotation when said shoe

is in retracted position and out of engagement when said shoe is in register with said buck, link means between said piston means and said yoke to effect rotation thereof upon movement of said piston means, and means biasing said shoe carriage into engagement with said yoke element.

2. An ironing machine according to claim 1 in which said last-named means comprise spring means in engagement with said shoe carriage and distorted by movement thereof into said registering position to accumulate energy sufficient to throw said carriage in a reverse direction through an overcenter position upon retraction of said yoke relative to said carriage, thereby insuring return of said carriage to a position at which gravity will assist the completion of carriage movement to retracted position.

3. An ironing machine, comprising a frame structure, a pair of mutually cooperating press members, means including a carriage for mounting one of said members, said carriage being pivoted relative to the other of said members for movement in a vertical plane transversely of the other member into and out of register therewith, means for moving said members cooperatively into registering position comprising hydraulic motor means including a cylinder pivotally mounting said carriage and fixed relative to said frame, the axis of said cylinder being in the plane of rotation of said carriage and symmetrical with relation to said carriage, combined piston and fluid pressure generation means within said cylinder for generating fluid pressure for application against the head of said piston for propulsion thereof, said pressure generation means including an externally controllable electric-motored pump drawing on a reservoir of liquid within said cylinder, means for securing the other of said press members on said piston for propulsion thereby, a yoke pivoted relative to said frame for movement in parallelism with said carriage, said yoke having an element releasably engaging directly with said carriage along an area on the carriage spaced from the pivotal mounting thereof when said press members are out of register, link means between the piston and the yoke to effect rotation thereof upon movement of said piston, and means biasing said shoe carriage into engagement with said yoke element, said biasing means being effective to supplement the weight of said press members in returning the piston means to its initial position upon interruption of operation of said pump means.

4. An ironing machine comprising a frame structure, a pair of mutually cooperating press members, means including a carriage for mounting one of said members, said carriage being pivoted relative to said other press member for movement in a vertical plane transversely of the other member into and out of register therewith, means for moving said members cooperatively into registering position comprising hydraulic motor means including a cylinder pivotally mounting said carriage and fixed relative to said frame, the

axis of said cylinder being in the plane of rotation of said carriage and symmetrical with relation thereto, piston means within said cylinder and means for generating fluid pressure within said cylinder to drive said piston therein, means for securing the other of said members on said piston means for propulsion thereby, a yoke pivoted eccentric with respect to said carriage but swingable in parallelism therewith, said yoke straddling said carriage and having a member extending thereacross, link means connecting said yoke member and said piston to enforce rotation of said yoke by said piston means on said yoke member engaging with said carriage in spaced relation to its pivotal mounting, only when said press members are out of register to enforce rotation of said carriage upon rotation of said yoke, and means for resiliently biasing said carriage to the non-registering position of said press members.

5. An ironing machine comprising a frame structure, a pair of mutually cooperating press members movable into and out of a registering position, means including a carriage for mounting one of said members, means for moving said members cooperatively into registering position comprising hydraulic motor means including a cylinder pivotally mounting said carriage and fixed relative to said frame, the axis of said cylinder being in the plane of rotation of said carriage, piston means within said cylinder and means for generating fluid pressure within said cylinder to drive said piston means therein, means for securing the other of said members on said piston means for propulsion thereby, a yoke pivoted eccentrically with respect to said carriage but swingable in parallelism therewith, said yoke straddling said carriage and having a member extending thereacross, link means connecting said yoke member and said piston means to enforce rotation of said yoke by said piston means, a cam on said carriage in spaced relation to the pivotal axis thereof, a cam follower on said yoke releasably engaging said cam, said cam being shaped to produce an initial rapid rate of movement of said carriage commencing with the out-of-register position of said members and progressively decreasing rates of movement as the in-register position is approached with substantially uniform movement of said yoke, and means resiliently biasing said carriage to the out-of-register position of said members.
